UNITED STATES PATENT OFFICE.

GEORGE A. ALEXANDER, OF PHILADELPHIA, PENNSYLVANIA, ASSIGNOR
TO WILLIAM LINKER, OF PHILADELPHIA, PENNSYLVANIA.

DESIGN FOR A PLATE OR SIMILAR ARTICLE.

No. 38,365.

Specification for Design.

Patented Dec. 18, 1906.

Application filed September 22, 1906. Serial No. 335,818. Term of patent 7 years.

To all whom it may concern:

Be it known that I, GEORGE A. ALEXANDER, a citizen of the United States, residing at Philadelphia, in the county of Philadelphia and State of Pennsylvania, have invented a new, original, and ornamental Design for Plates or Similar Articles; and I do hereby declare that the same is fully and clearly illustrated in the accompanying drawing, forming part of this specification.

The figure is a plan view of a plate, showing my new design.

I claim—

The ornamental design for a plate or similar article as shown.

GEORGE A. ALEXANDER.
